UNITED STATES PATENT OFFICE.

FREDERICK W. ORDING, OF JERSEY CITY HEIGHTS, NEW JERSEY, ASSIGNOR TO PERLEY & BROTHER, A CORPORATION OF NEW YORK.

DESIGN FOR A BROOCH.

No. 39,602.

Specification for Design.

Patented Oct. 6, 1908.

Application filed July 29, 1908. Serial No. 446,020. Term of patent 3½ years.

To all whom it may concern:

Be it known that I, FREDERICK W. ORDING, a citizen of the United States, residing at Jersey City Heights, Hudson county, New Jersey, have invented a new, original, and ornamental design for a Brooch, of which the following is a specification, reference being had to the accompanying drawing, forming part thereof.

The figure is a plan view of a brooch showing my new design.

I claim:

The ornamental design of a brooch as shown.

FREDERICK W. ORDING.
